GUN BARREL MOUNTING

Samuel G. Green, Gray, Ga.

Application July 8, 1940, Serial No. 344,363

17 Claims. (Cl. 89—14)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a mounting for moving gun barrels, especially where the muzzle end of the barrel is provided with a recoil check and accelerator, and constitutes an improvement upon my U. S. co-pending application Serial No. 302,553 filed November 2, 1939.

It is an object of the present invention to so improve the structure of my co-pending application as to provide a broaching action of such character that relative large particles of carbon or other residue cannot form and thereafter break or be broken away by the broaching action and cause ignition of the gas in the booster chamber.

It is a further object to provide means for broaching the bearing surfaces of the structure of the co-pending application, on which carbon or other residue tends to collect, in a manner to positively eliminate fouling of a character that will impede free recoil of the moving barrel.

A still further object of the invention is to provide a structure characterized to function in accordance with the above stated objects and additionally characterized by having a booster operating piston of smaller diameter than the barrel bearing whereby the barrel may readily be mounted in and removed from a water cooled gun without damage to the barrel packing.

With the increased speed or cyclic rate of automatic weapons demanded to-day, and the intricate installations which are only accessible with considerable difficulty, such as in the modern airplane, it has become essential that speed or rate accelerators be employed, and that to achieve the full advantage of employing this expedient the barrel mounting within the accelerator be so designed, in the case of recoiling barrels, that the formation of fouling incident to firing, of ice when the plane is in flight and the gun out of action, or any accumulation on the barrel mounting that tends to or causes binding which reduces the free recoil of the barrel and thus the operating reserve of the gun, be absolutely precluded. Means of a character which are automatic in operation must be employed to keep the bearing surface or surfaces for the barrel within or adjoining the accelerator clean as it is not sufficient to rely on cleaning these parts manually due to the relative inaccessibility of the mount and the time consuming nature of the task. It will be appreciated that where the clearance be-

tween the bearing surfaces referred to is necessarily held within tolerances of a few thousandths of an inch that only a slight binding of the barrel bearing will cause a variable velocity of recoil thus reducing the operating cyclic rate throwing the important operating time cycle out of harmony.

A major problem is also presented in the application of a booster or accelerator to a liquid cooled gun wherein alternate heating and cooling of the barrel bearing adjacent the booster increases the fouling effect of the gases and residue of explosion. In addition to this problem consideration must also be given to the lubrication of the barrel mounting bearing and to the employment of metals or a combination of suitable metals that will withstand gas and adverse weather attacks when the gun is not cleaned following firing.

It is, therefore, a still further object of the invention to provide a combination of elements organized and arranged to overcome the above recited problems and difficulties.

The specific nature of the invention as well as other objects and advantages thereof will clearly appear from a description of a preferred embodiment, as shown in the accompanying drawing in which:

Fig. 1 is a fragmentary longitudinal sectional view showing the application of a barrel accelerator, similar to the one disclosed in my co-pending application, to the muzzle portion of an air cooled gun and the improved means for broaching the barrel bearing surfaces subjected to fouling;

Fig. 1a is an elevation of the plug used in the structure of Fig. 1 to form the acceleration and gas check chambers;

Fig. 2 is a view similar to Fig. 1 showing the application as made on a liquid cooled gun;

Figs. 3, 4 and 5 are views similar to Fig. 1 showing modifications of the broaching elements.

Fig. 6 is a sectional view of a modified form of barrel showing how the exterior muzzle portion may be used as a guide in lieu of the guide sleeves shown in Figs. 1 to 5.

A recoil check and barrel accelerator generally designated at A of a design contemplated as within the scope of and comparable to the accelerator of my co-pending application is suitably attached to the muzzle end portion of the gun as follows:

A generally cylindrical barrel guide sleeve 12 having a forward portion of reduced diameter as

indicated at 16 and preferably formed of an aluminum-bronze alloy of self-lubricating characteristics, one composition of which is known to the art as "greasy-bronze," is secured to the barrel 10 with its forward face disposed in fluid sealed planar relation with the forward face of the barrel and its body portion circumferentially spaced from the barrel to maintain interchange of heat between the sleeve and barrel to a minimum.

To provide a bearing for the barrel guide sleeve 12, a tubular member 17 formed of non-corrosive material is suitably secured to the forward portion of barrel jacket 11 in any conventional manner, as by the interthreaded engagement indicated at 18, and is formed interiorly adjacent its rear end portion to receive the sleeve 12 in very accurate bearing and guiding relation as shown at 19. As in the co-pending application referred to, the bearing sleeve 12 is longitudinally grooved throughout its portion cooperating with bearing 19 at suitably spaced circumferential intervals to reduce drag effected by the friction of so accurate a fit between the sleeve in its bearing 19 to a minimum. In the case of the instant sleeve, however, a circumferential groove 15 is formed intermediate the forward ends of the grooves and reduced portion 16 which facilitates machining of the grooves and serves an additional function of impeding the flow of gases into the grooves as will hereinafter more fully be made apparent.

The forward end portion of the member 17 projects forwardly of the muzzle of the barrel and is interiorly threaded or otherwise formed to receive a plug 26 with its rear face in substantially planar registration with the forward face of the barrel when the latter is in "in battery" position. The plug 26 is axially bored at 21 to form a projectile passage in alignment with the bore of the barrel and is inwardly recessed on opposite end faces forming truncated conical cavities 28 and 29 of suitable size to cooperate in providing acceleration and gas check chambers 30 and 31, respectively. Intermediate its ends the plug 26 is provided with exteriorly disposed arcuate flanges 32 having flats 32' therebetween to receive a tool when to be secured within the end of member 17 and adapted to abut a gasket 32 interposed therebetween and the end of the member 17 as shown in Figs. 1 and 1a.

Forwardly of the flanges 32 the plug is formed exteriorly in any suitable manner to receive a gas check member 33 which is interiorly formed to provide an axial cavity of forwardly decreasing cross sectional area terminating in a cylindrical projectile passage. A deflection shield 34 and/or gasket may be interposed between the rear end of the gas check member and forward faces of the arcuate flanges 32 on plug 26. The cavity within the gas check member cooperates with the recess 29 in the forward face of the plug 26 to form the gas check chamber 31 which is in communication with atmosphere by a suitable number and arrangement of ports 35.

The forward end portion 16 of sleeve 12 is further reduced to form a circumferential seat for receiving a broaching bearing ring 36 which is secured thereon by silver alloy brazing, upsetting or any other desirable method. The ring 36 is preferably formed of a material having a red hot hardness greater than that of the carbonaceous or residue deposit tending to collect in this zone, for which purpose a tungsten-cobalt-chromium

alloy known in the art as "stellite" has been found admirably adapted. While ring 36 has been described as a prefabricated ring it will be understood that a built up or puddled ring may be used. The inner surface of ring 36 is comprised of two longitudinally spaced cylindrical surfaces separated by a circumferential clearance groove presenting sharp broaching edges at the outer termini of the cylindrical surfaces and at the juncture of the latter surfaces with the groove. A complementary broaching bearing ring 37 is seated within a circumferential groove intermediate the ends of member 17 so as to circumscribe the ring 36 in registering relation in the "in battery" position of the barrel. The ring 37 is retained in position within its groove through abutting engagement with the rear end of plug 26 and has a bearing surface confronting the bearing surface of ring 36 identical therewith. Ring 37 is also made of the same material and method as ring 36 and its bearing surface clears that of ring 36 several thousandths of an inch positively eliminating undue drag between these surfaces which is maintained by the present invention due to the broaching action of the broaching surfaces, it being necessary to employ a high grade tool steel or its equivalent as used in reaming tools for such purpose due to the hardness and tenacity of the carbon deposits tending to form.

Ports 38 formed in member 17 as shown permit egress of gas from the acceleration chamber 30 through the clearance of bearing rings 36 and 37.

In the operation of the invention thus far described gases of explosion upon firing will collect in the acceleration chamber 30 exerting a forwardly directed force upon the plug 26, member 17, jacket 11 and therethrough reduce the forces acting in recoil, simultaneously with the action of reducing recoil the gases acting upon the forward faces of sleeve 12 and barrel 10 will supplement the forces acting to move the barrel in recoil and thereby boost the speed of recoil thereof or accelerate this phase of the cycle in operation. The gases collecting in chamber 30 will subsequently pass into chamber 31 and impart a forward drive to the walls of the gas check member which is transmitted to jacket 11 and the gun to further reduce recoil. From chamber 31 the gases will escape to atmosphere. As the barrel 10 reciprocates the bearing rings 36 and 37 will be self-clearing of any fouling or residue tending to collect thereon because of the broaching character of the bearings. Gas escaping through the clearance of the bearing rings is conducted to atmosphere through ports 38 and is substantially precluded from coming into contact with the bearing 19 by the deflection shoulder formed by the reduced portion 16 of the sleeve and groove 15 in rear thereof. Due to the self-lubricating characteristics of the sleeve 12 the bearing 19 is adequately lubricated.

With the arrangement above described it has been found that necessity for disassembling the gun to remove carbon deposits and other fouling from the bearings by reaming as presently practiced in the art, or to otherwise clean these parts and lubricate the same has been greatly reduced if not entirely eliminated.

The action of the expanding gases and recompression thereof on the ignition and combustion of residue having been previously described and being substantially the same as in the copending case above referred to is not herein repeated.

In Fig. 2 there is shown the application of

the present invention to a liquid cooled gun, similar parts being identified by the same reference characters. In this view the front end portion of a water jacket 40 is shown having a front end cap 41 secured thereto in fluid sealed relation and formed to provide a cylindrical barrel sleeve bearing 42 and barrel sleeve packing groove 43. A barrel and pump sleeve 44 formed of the same material as sleeve 12 is attached by means of an inturned forward end portion 45 to barrel 10 as in the case of Fig. 1, in this case, however, the bearing surface of the sleeve constitutes a plane cylindrical surface, the longitudinal grooves being omitted. Bearing member 17 is secured to the front end cap 41 with suitable packing material disposed within groove 43 to form a liquid sealed joint with the sleeve and bearing 19 therefor in front of bearing 42. The diameter of reduced portion 45 of the sleeve is so related to the diameter of the body thereof that ring 36 may be formed on portion 45 within the diameter of the body of the sleeve whereby the barrel 10, sleeve 44 and ring 36 may be removed as a unit rearwardly without damage to the sleeve packing through engagement with the broaching bearing ring 36. Ring 37 is assembled in member 17 in the same manner as in Fig. 1, the plug 26' in this case being shown for use in forming an acceleration chamber 30 only, it being understood, however, that a gas check chamber may be used with this form of the invention as in Fig. 1 if desired.

Figs. 3, 4 and 5 are views showing modifications of the broaching bearing rings 36 and 37 disclosed in Figs. 1 and 2. In the modified forms shown in these figures the rings are formed of the same material as rings 36 and 37 and assembled in position in the same general manner as the latter rings.

In Fig. 3 the inner bearing ring 36 is arranged on the barrel sleeve 12 as in Fig. 1 but the outer bearing ring 37' in this case is of sufficient width to overlap either end of ring 36 when the barrel is in its "in battery" position. The ring 37' also has two clearance grooves, one disposed on either side of a centrally located cylindrical bearing surface. By this arrangement escape of gas past the bearings 36, 37' is rendered more difficult and the centrally located bearing surface of ring 37', which normally registers with the clearance groove in ring 36 when the barrel is "in battery," has a more pronounced broaching action on ring 36 thereby increasing the efficiency of the arrangement in certain installations.

In Fig. 4 the rings 36 and 37 are so located on the barrel sleeve and bearing member 17 that they will be in longitudinally spaced relation in the "in battery" position of the barrel. In this arrangement gas in acceleration chamber 30 may initially pass through a relative unobstructed passage leading past the bearing rings 36 and 37, however, as the barrel 10 and its sleeve 12 recoil and the bearing rings 36 and 37 come into registration flow of gas past the bearing rings will be relatively obstructed with consequent greater force exerted on the barrel in a recoil direction. Through spacing the rings as described to obtain the consequent flow of gas, the acceleration imparted to the recoiling barrel by the reaction of the gas thereon will be more gradual than in the other forms of the invention where acceleration due to reaction of the gas is practically instantaneous. It has been found that an approximate spacing of one-sixteenth of an inch between adjacent ends of the

rings gives satisfactory results. This form of the invention is particularly adapted for use on guns when higher than ordinary muzzle pressures and gun speeds are used.

Fig. 5 discloses an arrangement of ring 36 as in the other forms of the invention in combination with a ring 37" of slightly different form. The ring 37" is shaped similarly to ring 36 but is of increased proportions and is disposed to be partially overlapped forwardly by ring 36 in the "in battery" position of the barrel 10.

The action in this form of the invention is similar to that of Fig. 3, but differs therefrom in that residue collecting on ring 36 will be more effectively broached by ring 37".

In both Figs. 4 and 5 it may be essential to employ a sleeve 46 interposed between the plugs 26' and rings 37 or 37" to retain the latter in position in member 17.

In all forms of the invention the working clearance between the broaching rings 36 and 37, 37' or 37" has been found to be most efficient when held within limits of one to four times the working clearance of bearing 19.

By the use of broaching rings as disclosed by this invention the surfaces of the broaching and boosting elements are kept from spalling, being cut by gas or abrasion or in any other way being roughened to invite deposits of carbon or other fouling. This is particularly important in installations not readily demountable for cleaning and is important in all installations to keep the gun in action.

The conventional barrel booster not being provided with the continuous self-cleaning action by broaching as in the instant case tends to form carbon deposits which will cause not only binding of the barrel but eccentricity thereof resulting in deleterious results, especially in aircraft mounts.

While in each of the forms of the invention disclosed a guide sleeve 12 has been shown attached to the muzzle portion of the barrel it will be understood by those skilled in the art that such sleeve may be omitted and the muzzle portion of the barrel 10' formed as shown in Fig. 6 to be directly received in the bearing 19 of tubular member 17. Where this latter expedient is employed the barrel 10' may also be formed to receive the broaching ring 36 and provided with a groove 15 for the same purpose that groove 15 is provided in the sleeve 12 of Fig. 1.

I claim:

1. In a weapon comprising a recoil barrel, a barrel jacket surrounding the barrel, a tubular member secured to the jacket in axial prolongation thereof, a bearing on said tubular member being formed to receive the barrel in accurately fitted bearing relation rearwardly of the muzzle end of the barrel, cooperating broaching rings secured to the barrel and tubular member forwardly of said bearing and having a working clearance of one to four times the clearance of the bearing, means on the tubular member forming an acceleration chamber adjacent the muzzle end of said barrel, and means in said tubular member establishing communication between the atmosphere and the accelerating chamber upon the recoil of the barrel and intermediate said bearing and broaching rings.

2. In a weapon comprising a recoil barrel, a barrel jacket surrounding the barrel, a tubular member secured to the jacket in axial prolongation thereof, a bearing sleeve secured to the muzzle end portion of the barrel in fluid sealed

relation, said tubular member being formed to receive the said sleeve in accurately fitted bearing relation rearwardly of the muzzle end thereof, cooperating broaching rings secured to the sleeve and tubular member forwardly of said bearing and having a working clearance of one to four times the clearance of the bearing, means on the tubular member forming an acceleration chamber adjacent the muzzle end of said sleeve and barrel, and means in said tubular member establishing communication between the atmosphere and accelerating chamber upon the recoil of the barrel and intermediate said bearing and broaching rings.

3. In a weapon comprising a recoiling barrel, a barrel jacket surrounding the barrel, a tubular member secured to the jacket in axial prolongation thereof, a bearing sleeve provided with a cylindrical body portion terminating in a forward portion of reduced section secured to the muzzle end portion of the barrel with its body portion spaced from the barrel radially and its forward portion in fluid sealed relation with the muzzle end of the barrel, said tubular member being formed to receive the body portion of said sleeve in accurately fitted bearing relation, a broaching ring of smaller diameter than said body portion, secured to the portion of said sleeve of reduced section, a cooperating broaching ring secured to said tubular member, the clearance between said broaching rings being one to four times the clearance of said bearing, means on the tubular member forming an acceleration chamber adjacent the muzzle end of said sleeve and barrel, and means in said tubular member establishing communication between the atmosphere and accelerating chamber upon the recoil of the barrel and intermediate said bearing and broaching rings.

4. In a weapon comprising a recoiling barrel, a barrel jacket surrounding the barrel, a tubular member secured to the jacket in axial prolongation thereof, a bearing sleeve provided with a cylindrical body portion terminating in a forward portion of reduced section secured to the muzzle end portion of the barrel with its body portion spaced from the barrel radially and its forward portion in fluid sealed relation with the muzzle end of the barrel, said tubular member being formed to receive the body portion of said sleeve in accurately fitted bearing relation, a broaching ring of smaller diameter than said body portion, secured to the portion of said sleeve of reduced section, a cooperating broaching ring secured to said tubular member, the clearance between said broaching rings being one to four times the clearance of said bearing, means on the tubular member forming an acceleration chamber adjacent the muzzle end of said sleeve and barrel, said tubular member being formed to provide ports communicating between the atmosphere and accelerating chamber upon the recoil of the barrel and intermediate said bearing and broaching rings, and the junction of the cylindrical body portion and forward reduced portion of said sleeve being so related to the ports that it will deflect gases flowing past said broaching rings into said ports.

5. A weapon comprising a recoiling barrel, said barrel being disposed in a liquid container having a front end cap formed to provide a bearing for the muzzle portion of the barrel, a bearing sleeve provided with a cylindrical body portion terminating in a forward portion of reduced section secured to the muzzle end portion of the

barrel with its body portion spaced from the barrel radially and its forward portion in fluid sealed relation with the muzzle end of the barrel, said front end cap bearing receiving the body portion of the sleeve in accurately fitted bearing relation, a tubular member secured to said front end cap in axial prolongation of the barrel and formed to receive the body portion of said sleeve in accurately fitted bearing relation forwardly of said first named bearing, packing material interposed between said bearings in liquid sealed engagement with the body of said sleeve, a broaching ring of smaller outside diameter than the corresponding diameter of said body portion of the sleeve secured to the forward portion of reduced section thereof, a cooperating broaching ring secured to said tubular member, the clearance between said broaching rings being one to four times the clearance of said bearings, means on the tubular member forming an acceleration chamber adjacent the muzzle end of said sleeve and barrel, and means in said tubular member establishing communication between the atmosphere and accelerating chamber upon the recoil of the barrel and intermediate said bearings and broaching rings whereby said barrel, sleeve and broaching ring attached to the sleeve may be removed from the gun as a unit without damage to said packing.

6. The structure of claim 5 wherein said front end cap is interiorly grooved circumferentially forwardly of the bearing therein to receive said packing.

7. The structure of claim 5 wherein said front end cap is interiorly grooved circumferentially forwardly of the bearing therein to receive said packing and the rear portion of said tubular member.

8. In a weapon comprising a recoiling barrel, a barrel jacket surrounding the barrel, a tubular member secured to the jacket in axial prolongation thereof, a bearing sleeve secured to the muzzle end portion of the barrel in fluid sealed relation, said tubular member being formed to receive the sleeve in accurately fitted bearing relation rearwardly of the muzzle end thereof, complementary broaching rings secured to the bearing sleeve adjacent its muzzle end and the tubular member disposed to be in registering relation in the "in battery" position of the barrel, said broaching rings having a working clearance of one to four times the clearance of the bearing, means forming an acceleration chamber adjacent the muzzle end of said sleeve and barrel, and means in said tubular member establishing communication between the atmosphere and accelerating chamber upon the recoil of the barrel and intermediate said bearing and broaching rings.

9. The structure of claim 8 wherein said broaching rings are provided with confronting annular clearance grooves.

10. In a weapon comprising a recoiling barrel, a barrel jacket surrounding the barrel, a tubular member secured to the jacket in axial prolongation thereof, a bearing sleeve secured to the muzzle end portion of the barrel in fluid sealed relation, said tubular member being formed to receive the sleeve in accurately fitted bearing relation rearwardly of the muzzle end thereof, a broaching ring secured to the forward portion of said sleeve, a cooperating broaching ring of greater width than said first named broaching ring secured to the tubular member in overlapping relation to either end of the latter in the "in battery" position of the barrel, said

broaching rings having a working clearance of one to four times the clearance of the bearing, means on the tubular member forming an acceleration chamber adjacent the muzzle end of said sleeve and barrel, and means in said tubular member establishing communication between atmosphere and the interior thereof at points intermediate said bearing and broaching rings.

11. The structure of claim 10 wherein said first recited bearing ring is provided with a clearance groove and said broaching ring of greater width is provided with a plurality of spaced clearance grooves confronting and disposed with an adjacent groove wholly to either side of the groove in said first recited broaching ring.

12. In a weapon comprising a recoiling barrel, a barrel jacket surrounding the barrel, a tubular member secured to the jacket in axial prolongation thereof, a bearing sleeve secured to the muzzle end portion of the barrel in fluid sealed relation, said tubular member being formed to receive the sleeve in accurately fitted bearing relation rearwardly of the muzzle end thereof, complementary broaching rings secured to the barrel sleeve adjacent its muzzle end and the tubular member disposed to have adjacent ends in spaced relation in the "in battery" position of the barrel; said broaching rings having a working clearance of one to four times the clearance of the bearing, means on the tubular member forming an acceleration chamber adjacent the muzzle end of the sleeve and barrel, and means in said tubular member establishing communication between atmosphere and the interior thereof at points intermediate said bearing and broaching rings.

13. The structure of claim 12 wherein said broaching rings are provided with annular confronting clearance grooves.

14. In a weapon comprising a recoiling barrel, a barrel jacket surrounding the barrel, a tubular member secured to the jacket in axial prolongation thereof, a bearing sleeve secured to the muzzle end portion of the barrel in fluid sealed relation, said tubular member being

formed to receive the sleeve in accurately fitted bearing relation rearwardly of the muzzle end thereof, a broaching ring secured to the forward portion of said sleeve, a cooperating broaching ring of greater width than said first named broaching ring secured to the tubular member in overlapping relation to the forward end of the latter in the "in battery" position of the barrel, said broaching rings having a working clearance of one to four times the clearance of the bearing, means on the tubular member forming an acceleration chamber adjacent the muzzle end of said sleeve and barrel, and means in said tubular member establishing communication between atmosphere and the interior thereof at points intermediate said bearing and broaching rings.

15. The structure of claim 14 wherein said broaching rings are provided with similar confronting annular clearance grooves.

16. In a weapon comprising a recoiling barrel, a barrel jacket surrounding the barrel, a tubular member of non-corrosive material secured to the jacket in axial prolongation thereof, a self-lubricating aluminum-bronze alloy bearing sleeve secured to the muzzle end portion of the barrel in fluid sealed relation, said tubular member being formed to receive the said sleeve in accurately fitted bearing relation rearwardly of the muzzle end thereof, cooperating broaching rings formed of a tungsten-cobalt-chromium alloy secured to the sleeve and tubular member forwardly of said bearing and having a working clearance of one to four times the clearance of the bearing, means on the tubular member forming an acceleration chamber adjacent the muzzle end of said sleeve and barrel, and means in said tubular member establishing communication between atmosphere and the interior thereof at points intermediate said bearing and broaching rings.

17. The structure of claim 16 wherein said broaching ring on the bearing sleeve is secured thereon by means of silver alloy brazing.

45 SAMUEL G. GREEN.
